CLAIM

The ornamental design for a “magnetic curtain rod bracket,” as shown and described.

DESCRIPTION

FIG. 1 is a front right side perspective view of a “magnetic curtain rod bracket” showing my new design;

FIG. 2 is a front elevational view thereof;

FIG. 3 is a right side elevational view thereof, the left side being a mirror image thereof;

FIG. 4 is a top plan view thereof;

FIG. 5 is a rear elevational view thereof; and,

FIG. 6 is a bottom plan view thereof.
